UNITED STATES PATENT OFFICE

RAYMOND M. BROWN, OF NEWPORT NEWS, VIRGINIA

BOTTLE OPENER

Application filed September 13, 1928. Serial No. 305,843.

This invention relates to bottle opener of the cork remover type, and is particularly designed as a combination instrument to effect the removal of crown caps from bottles 5 and the removal of corks from the bottle necks.

The invention is designed for use in hotels and similar places in order to avoid the constant marring of furniture by the attempts 10 of guests to remove caps and corks from bottles by applying them to the edges of furniture, radiators, etc., or by utilizing instruments ill adapted for removal of bottle closures.

15 The object of the present invention is to provide a combination cap remover and cork remover which can be fixed securely to a vertical surface and at a convenient height for use, and adapted to facilitate the removal 20 of crown caps and corks from bottle necks.

Another object of the invention is to provide a device of the character referred to which can be very cheaply manufactured and which can be very readily assembled and positioned in any desired and suitable location. 25

Other objects of the invention will become apparent as the detailed description thereof proceeds.

In the drawings:

30 Fig. 1 is a perspective view of the bottle opener applied to a vertical surface;

Fig. 2 is a front elevation of the bottle opener;

Fig. 3 is a vertical section taken on the 35 line 3—3 of Fig. 2;

Fig. 4 is a vertical section taken on the line 4—4 of Fig. 3, and illustrating the elements of this opener in rear elevation; and

40 Fig. 5 is a perspective view of a corkscrew guard forming one of the elements of this invention.

The invention comprises a member 1 having a substantially flat rear surface 2, adapted to be secured against the substantially vertical wall. The member 1 is recessed as designated by the numeral 3 to ensure contact of the outer edges of the surface 2 with the vertical wall to which the instrument may be secured.

45 The recessed portion 3 is continued to the

lower part of the member 1 to form shoulders 4 and 5 parallel to each other, and adapted to contact with the edges 6 and 7, respectively, of a corkscrew guard 8, which forms another one of the main elements of the invention.

The corkscrew guard 8 has its upper end enlarged to seat in the recessed portion 3; and this enlargement 9 is provided with a circular aperture 10, adapted to receive a boss 11 (see Fig. 4) which serves to hold the guard 8 from longitudinal separation from the member 1 when the parts of the invention are assembled and secured in position on the wall.

The boss 11 is substantially of the same thickness as the thickness of the metal of the enlargement 9 of the guard, which in turn is equal in thickness to the depth of the recessed portion 3 between the shoulders 4 and 5.

The guard 8 has the lower part thereof bent up to form flanges 12 and 13, adapted to receive between them the curved part of a corkscrew 14 which is pivoted at its upper end to a pin 15 held frictionally in apertures formed in a bifurcated projection 16, extending laterally from the bottom of the member 1.

The member 1, at its upper end, is provided with a hollow recessed portion projecting laterally from the main portion of body 1 at an obtuse angle. This portion 17 is provided at its outer edge with an annular flange 18, adapted to impinge against the lower edge of the rim of a crown cap in common use on narrow necked bottles. The rear end of the portion 17 has a lug 19 projecting at an obtuse angle from and formed integral with the member 1. This lug 19 forms a fulcrum adapted to contact with the top of a crown cap; and is spaced relative to the annular flange 18 so that a bottle neck with a crown cap thereon may be conveniently located to effect removal of the cap in the well known manner.

The guard 8 and member 1 are secured in position against the vertical surface W by means of screws 20, 21 and 22. One of these screws, 22, passes through the boss 11 and thus secures the member 1 and guard 8 in position on the surface W.

It will be apparent from the drawings that when the members 1 and 8 of this invention are assembled as shown, the shoulders 4 and 5 prevent lateral swinging movement of the guard 8 relative to the member 1. The flanges 5 12 and 13 prevent injury to the corkscrew 14, and at the same time serve as a guard to prevent the point of the corkscrew catching on the clothing of persons who may be passing by.

10 The overhanging crown cap remover 17 also forms a guard for the corkscrew to prevent injury thereto and to prevent contact therewith of the clothing of persons who may be passing by. The frictional engagement of the corkscrew 14 with the pivot 15 and the lug 16 enables the corkscrew to be positioned at any desired angle relative to the face of the surface W which may be found most convenient for use.

20 What I claim is:

1. A cork remover comprising a sheet metal base having a flat surface adapted to be applied to a similar surface and having flanges 25 at each side thereof parallel to each other and extending partly along said base, a plate having a recess in the back thereof adapted to receive the unflanged part of said base and having shoulders engageable with the edges 30 of said base to prevent rotation of the base and plate relative to each other, a corkscrew pivoted to swing into and out of the space between said flanges, and means for securing said base and plate to each other and to a 35 substantially flat surface.

2. A wall-type bottle closure remover comprising a relatively massive part, a cork screw pivoted directly to said massive part, and a sheet metal cork screw guard of relatively 40 frail construction positioned below said massive part interfitting with the latter and in unitary relation therewith, said guard being formed as an open-faced channel into which said cork screw swings by gravity.

45 3. A wall-type bottle closure remover comprising a relatively massive part, a cork screw pivoted directly to said part, and a sheet metal cork screw guard of relatively frail construction, said relatively massive and frail 50 members having inter-fitting portions at the rear of said relatively massive part, constructed to inhibit relative rotation between said members, and means for securing the cork remover to the wall, passing through 55 aligned openings in said inter-fitting portions.

In testimony whereof I affix my signature.

RAYMOND M. BROWN.
